JOEL D. LUNDQUIST AND JOSEPH BUXBAUM, OF BROOKLYN, NEW YORK, ASSIGNORS
TO CAPITOL HAT BLOCK CO., INC., OF NEW YORK, N. Y.

HAT BLOCK

Application filed May 20, 1929. Serial No. 364,368.

Our invention relates to blocks such as are used in the manufacture of hats.

Hat blocks are forms on which manufacturers shape the hats to conform with prevailing fashions. Since the advent of the so called "helmet" type of ladies hat, partly as an echo of the late war and partly because of the fashion of bobbing the hair, the lack of opportunity for displaying their talents in fanciful designs has led manufacturers to the necessity of giving a great variety of shapes to the crown of the hat, while preserving the general helmet style. Just as the helmet hat is pulled tightly over a woman's head, so, in the manufacture of hats, these are pulled tightly over the hat block. The hat block, therefore, takes the shape not of the cranium, but of the hair covered head, as distinguished from a block used to pin a wig on, in which case the block is shaped like the cranium.

Now, such a hat block, if placed on a base, without any suggestion of a human face below the block, as has been the common practice heretofore, has this disadvantage: it fails to give the manufacturer or designer of the hat any indication whether, or not, the contours of the hat harmonize with the face. The hat may look well enough on the block, but, when placed on a woman's head, it may totally fail to give the desired effect. For this reason, some manufacturers try the hats on model busts, made of wood, metal, or plaster of Paris. But here, again, the difficulty arises in that the same bust, having the same head, will not fit every hat and, unless the manufacturer is supplied with a vast quantity of busts with variously shaped heads, which is not only an extremely costly, but an impractical arrangement because of the enormous space required for such a collection of busts, he is without the necessary means for judging of the probable effect of any hat on any particular head.

In the practice of the present invention, designed to overcome the above stated difficulties, the hat block is placed on a pedestal simulating a human bust but having only the lower part of a head, the upper part of the head being replaced by the hat block, the

contours of this hat block being those of a hair covered head and not those of a cranium. The hat blocks used in the practice of this invention are distinguished from the ordinary, commonly used hat blocks in that their under surface has a periphery corresponding to the lowest contact periphery of the hat, i. e. the lowest periphery of contact between the hat and the human head upon which the hat is to be ultimately placed. As to the under surface of the block, this may be plane, convex, or concave, the choice depending on the style of hat for which it is intended. The lowest contact periphery may be otherwise defined as the limit to which the hat may be pulled over the block, corresponding to the limit to which the same hat may be pulled over the head of the actual wearer.

In this manner, when the block is placed on the mutilated head of the pedestal, and a hat is pulled over the block, the block is entirely concealed from view, and only the lower part of the head is visible under the hat, thus giving the illusion necessary to the manufacturer in order that he may gage the effect which the hat will produce on an actual head.

Nor is it necessary in all cases to have the lowest periphery of contact, or the lowest limiting periphery of the block, coincide with the periphery of the upper surface of the mutilated head, since the hat will conceal the break in continuity, as is illustrated in Figures 5 and 6 of the drawings. All that is necessary is that the lowest contact periphery of the block be in conformity with the lowest contact periphery of the hat when the latter is placed on the head of the wearer.

In the drawings, Figures 1 to 4 are front elevations of various embodiments of this invention, Figure 1 showing a hat block having a slanting contact with the pedestal's mutilated head, Figure 2, a horizontal contact, Figure 3 a sectional block upon the pedestal, and Figure 4 a block and pedestal with a hat pulled over the block. In Figures 5 and 6, which are also front elevations, the under surface of the block extends beyond the upper surface of the mutilated head, Figure 5 showing the pedestal with the hat

block, and Figure 6 the same pedestal and hat block with a hat pulled over the block. Figures 7 and 8 are front elevations of sectional blocks, the sections of the blocks being separated. Figure 9 is a detail of the connection between the block and the mutilated head or between the sections of the same block.

In these figures, 1 is the pedestal; 2 the hat block, when it is made of a single piece, or 2' and 2'', when it is made up in sections, as in Figure 3; 3 is a hat; 4 a hole in the block 2, or in the sections 2' and 2'' of the sectional block; 5, 5 are pegs or pins on the mutilated head of the pedestal 1, having an enlarged portion 6 at the top; 7 are spring fingers attached to the block, as by means of a screw 8, to hold the pegs 5 in place.

In the case of women's hats, it is preferable to give a certain slant to the block in order to conform with prevailing styles, which is accomplished by inclining the under surface of the block and giving a corresponding inclination to the upper surface of the mutilated head of the pedestal, as in Figure 1.

The same pedestal may be used in conjunction with a variety of hat blocks, which are interchangeable, thus securing the same result as would be obtained by a collection of various busts, but without the expense and great consumption of space which such a collection entails. Instead of using a single block, a sectional block may be employed, the sections being superimposed as shown in Figure 3. This permits the use of blocks with plane or curved under surfaces on the same pedestal.

The block may be affixed to the mutilated head in various ways. Such expedients are so well known in the art that the simple illustration shown in the drawing is deemed sufficient. As shown, when the block is placed upon the pedestal, two pegs 5, 5, projecting from the top of the mutilated head enter corresponding holes 4, 4, in the block and are firmly but releasably held therein by the spring fingers 7 which are attached to the block as by means of a screw 8. In order to more firmly secure the pegs in the block, the pegs are enlarged at the top, as at 6, and the spring fingers 7 are curved in such a manner that they close upon the pegs 5 after these have been forced into the holes 4, on the familiar principle of a snap catch.

We claim:

1. The combination with an interchangeable block for a hat, which block is externally formed to the configuration of the crown of a human head, including the hair thereon, of a pedestal therefor formed at its upper end to simulate the lower part including the face of said head, the periphery of the lower edge of said block conforming to the lowest contact periphery of said hat, and means for releasably securing said block to said head part.

2. The combination with an interchangeable block for a hat, which block is externally formed to the configuration of the crown of a human head, including the hair thereon, of a pedestal therefor formed at its upper end to simulate the lower part including the face of said head, the periphery of the lower edge of said block conforming to the lowest contact periphery of said hat, the bottom surface of said block and the top surface of said pedestal being plane, and means for separably securing said block to said head part when said plane surfaces are in contact.

3. The combination with an interchangeable block for a hat, which block is externally formed to the configuration of the crown of a human head, including the hair thereon, of a pedestal therefor formed at its upper end to simulate the lower part including the face of said head, the periphery of the lower edge of said block conforming to the lowest contact periphery of said hat, the bottom surface of said block and the top surface of said pedestal being plane and having a slant relatively to the upright position of the head, and means for separably securing said block to said pedestal when said slanting plane surfaces are in contact.

4. The combination with an interchangeable sectional block for a hat, which block is externally formed to the configuration of the crown of a human head, including the hair thereon, of a pedestal therefor formed at its upper end to simulate the lower part including the face of said head, the periphery of the lower edge of said block conforming to the lowest contact periphery of said hat, and means for separably securing the sections of said block to one another and to said pedestal.

In testimony whereof we have affixed our signatures.

JOEL D. LUNDQUIST.
JOSEPH BUXTAUM.
